US00D893462S

(12) **United States Design Patent** (10) **Patent No.:** **US D893,462 S**
Liu (45) **Date of Patent:** **** Aug. 18, 2020**

(54) **HEADPHONE**

(71) Applicants: **Shenzhen Humboldt Technology Co., Ltd.**, Shenzhen (CN); **Guang Dong Esthetical Her Industrial Investment Co., Ltd.**, Dongguan (CN)

(72) Inventor: **Murong Liu**, Ganzhou (CN)

(**) Term: **15 Years**

(21) Appl. No.: **29/726,687**

(22) Filed: **Mar. 5, 2020**

(51) LOC (12) Cl. **14-01**

(52) U.S. Cl.

USPC **D14/223**

(58) **Field of Classification Search**

USPC D14/223, 205; D24/174; 128/864; 381/322, 328, 370, 380, 381; 455/90.3, 455/575.1, 569.1
 CPC H04R 1/10; H04R 25/00; H04R 1/1066; H04R 1/1016; H04R 5/033; H04R 5/0335; H04R 1/105; H04R 1/1041; H04R 1/1083; H04R 1/1058

See application file for complete search history.

(57) **CLAIM**

The ornamental design for a headphone, as shown and described.

DESCRIPTION

FIG. 1 is a first perspective view of a headphone showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines depict environment that is for illustrative purposes only; the broken lines form no part of the claimed design.

1 Claim, 8 Drawing Sheets
